UNITED STATES PATENT OFFICE.

HARRY SCHWARZ, OF ST. LOUIS, MISSOURI.

DESIGN FOR A MIDDY WAIST OR BLOUSE.

46,415.

Specification for Design.

Patented Sept. 15, 1914.

Application filed February 2, 1914. Serial No. 816,104. Term of patent 3½ years.

To all whom it may concern:

Be it known that I, HARRY SCHWARZ, a citizen of the United States, residing at the city of St. Louis, State of Missouri, have invented a new, original, and ornamental Design for a Middy Waist or Blouse, of which the following is a specification, reference being had to the accompanying drawings, forming a part hereof, in which—

Figure 1 is a perspective view of the front of a middy waist or blouse embodying my new design; and Figs. 2 and 3 are, respectively, side and rear perspective views of the same.

I claim—

The ornamental design for a middy waist or blouse, substantially as shown.

HARRY SCHWARZ.
